UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed June 14, 1924. Serial No. 719,924.

This invention aims to provide an improved separable fastener.

In the drawings, which illustrate a preferred embodiment of my invention:—

5 Figure 1 is a front elevation of the preferred fastener;

Fig. 2 is a section on the line 2—2 of Fig. 1, being partly in elevation, and showing the stud and socket locked together;

10 Fig. 3 is a section similar to Fig. 2, and shows the stud moved axially into the socket and the locking member in unlocked position;

15 Fig. 4 is a section similar to Fig. 2 and shows the stud being separated from the socket by relative tipping action after the parts have assumed the position in Fig. 3;

Fig. 5 is a front elevation of the stud;

Fig. 6 is a rear elevation of the stud;

20 Fig. 7 is a section on the line 7—7 of Fig. 1, showing the means of attaching the stud to a curtain;

Fig. 8 is a front elevation of the socket;

Fig. 9 is a side elevation of the socket and

25 Fig. 10 is a section of a portion of a socket showing a tapered locking member.

Referring to the drawings and to the preferred form of my invention, I have shown a socket including a casing 1 presenting a stud-receiving aperture, a screw 2 for attaching the casing to the body 3 of an automobile or the like, and a spring-pressed locking member 4 normally surrounded by the stud-receiving aperture.

30 The socket, as illustrated, except for the locking member, is substantially like the one illustrated and described in the co-pending application of Andrew G. Anderson, Serial No. 708,724, filed April 24th, 1924.

35 The preferred form of stud illustrated is of very simple and inexpensive construction and comprises a socket-engaging contractible and expandible head struck up from a single sheet of metal and having a substantially long neck 5 for engagement with the stud-receiving aperture. The base 6^a of the stud presents a plurality of prongs 6 (Figs. 6 and 7), which are adapted to pierce the

40 stud-carrying fabric such as the curtain 7 of an automobile, thereby to engage and be clenched outwardly and downwardly by a one-piece clench plate 8 located upon the front side of the curtain.

A latch 9 is pivoted upon the stud mem-

ber and operates in a slot therein to displace 55 the locking member as more fully herein-after described. The latch is held in position by an inwardly bent ear 10, which also provides a smooth guiding surface for the latch, as best illustrated in Figs. 2, 3, 4 and 60 6. This ear 10 extends inwardly from the edge of the base 6^a (Figs. 2 and 6) and is made relatively wide so as to be supported by the front plate when the stud is attached to the curtain.

65 The clench plate presents a false press-button 11 integral therewith to designate the point at which the fastener may be pressed to engage the stud with the socket. Pressure upon this "press-button" causes the head of 70 the stud to enter the stud-receiving aperture in the socket and contract slightly before coming into contact with the locking member 4. Thus the locking member is excluded 75 from the stud and is urged inwardly until the head of the stud passes through the aperture whereby it again expands and the locking member is urged into the head of the stud, thus locking the stud and socket together and preventing separation thereof by 80 a strain exerted at any side of the fastener.

When the stud and socket are locked together, as illustrated in Fig. 2, the inner end 12 of the latch is engaged by the locking member and swung about its pivot until the outer end 13 of the latch is seated against the front face of the socket. As illustrated, the spring-pressed sealing disc 14 urges the stud outwardly from the socket until that portion of the head of the stud, beyond the neck, is seated against the peripheral wall surrounding the stud-receiving aperture.

85 Separation of the stud from the socket may be effected by exerting pressure upon the false press-button, thereby urging the 90 stud bodily toward the socket, which movement is permitted by the relatively long neck which may slide relative to the wall surrounding the stud-receiving aperture. This 95 relative axial movement between the stud and the socket exerts pressure upon the outer end 13 of the latch, thereby tipping it about its pivot whereby the inner end 12 of the latch moves the locking member out of engagement with the contractible and expansible head, as best illustrated in Fig. 3. The 100 stud may now be separated from the socket by grasping the lower edge of the curtain

2 and exerting a slight pull thereon, as illustrated in Fig. 4.

By providing the socket with a tapered locking member, as illustrated in Fig. 10, 5 the stud may be separated from the socket by an outward pull at the bottom of the curtain, without the initial inward pressure on the stud, the lever 9 being rocked by the resolution of forces, sufficiently to start the 10 locking member 4 out of locking position and the taper thereof progressively increasing the clearance as the stud is tipped out of the socket. In such case, however, an upward pull on the curtain would by resolution of forces produce a similar tipping 15 movement, making the fastener less secure and dependable for uses where the stud-carrying medium may exert an upward pull on the socket. To prevent this resolution of 20 forces arising from an upward pull, I have provided on the socket an abutment, herein shown as the inner face of the ringlike peripheral bead 15 provided on the front face 25 of the socket. The upper edge of the adjacent end 13 of the lever 9 abutting against the inner face of the bead 15, rocks the lever 9 in the opposite direction from that which moves the locking member 4 out of locking 30 position. This abutment is provided whether the locking member has straight or tapered sides so as to insure against separation of the stud and socket by an upward strain on the curtain.

While I have shown and described a preferred form of one embodiment of my invention, it will be understood that changes involving omission, alteration, substitution and reversal of parts, and even changes in the mode of operation, may be made without departing from the scope of my invention, which is best defined in the following claims.

I claim—

1. A separable fastener comprising, in combination, a flush type socket having a front face, a stud for application to a flexible carrying medium, said stud having a head for engagement with said socket, locking means carried by said socket for locking 45 said stud and socket together and unlocking means carried by said stud, said unlocking means having a portion for engagement with the front face of the socket and another portion for engagement with the locking member whereby movement of the stud toward the socket operates said unlocking means to shift said locking means and permit separation of said stud and socket.

2. A separable fastener comprising, in combination, a stud element and a socket element, said socket element having a front face, locking means carried by one of said elements for locking them together and unlocking means carried by the other of said elements, said unlocking means having a

portion for engagement with the front face of the socket and another portion for engagement with the locking member whereby movement of the stud toward the socket operates said unlocking means to displace the locking means and permit separation of the fastener by tipping the stud relative to the socket. 70

3. A separable fastener comprising, in combination, a socket presenting a front face having a stud-receiving aperture therethrough, a spring-pressed locking member forming a part of the fastener assembly and normally extending into said aperture, a stud having a contractile and expansible head for engagement in said aperture and with said locking member to lock said stud and socket together and an unlocking member also forming a part of the fastener assembly, said unlocking member having a portion for engagement with the front face of the socket and another portion for engagement with the locking member whereby movement of the stud toward the socket operates said unlocking member to displace said locking member and permit separation of said stud from said socket. 85

4. A separable fastener comprising, in combination, a socket presenting a stud-receiving aperture, a spring-pressed locking member forming a part of the fastener assembly and normally extending into said aperture, a stud having a contractile and expansible head for engagement in said aperture and with said locking member to lock said stud and socket together, and an unlocking member pivoted upon said stud and operable to shift said locking member out of engagement with said head to permit separation thereof from said socket. 95

5. A separable fastener comprising, in combination, a socket presenting a stud-receiving aperture, a spring-pressed locking member forming a part of the fastener assembly and normally extending into said aperture, a stud having a contractile and expansible head for engagement in said aperture and with said locking member to lock said stud and socket together, and a latch pivoted upon said stud having one end thereof bearing against the front face of said socket and the other end bearing against the locking member, said stud shiftable relative to said socket thereby tipping said latch relative to said stud to move said locking member into unlocking position. 110

6. A separable fastener comprising, in combination, a socket presenting a stud-receiving aperture, a stud having a contractile and expansible head for engagement in said aperture, spring-pressed locking means forming part of the fastener assembly for locking said head in said aperture and a latch pivoted upon said stud, said latch operable by pressing said stud axially toward 120

said socket thereby to displace said locking means and permit tipping said stud out of engagement with said socket.

7. A stud for a separable fastener including a back plate presenting an annular socket-engaging contractile and expansible head provided with an annular aperture for reception of a locking member which forms part of a socket with which the stud may 10 be engaged, a latch pivoted upon said stud and operative relative thereto for unlocking said stud when secured to a socket, and means for securing said stud to flexible carrying fabric.

15 8. A stud for a separable fastener including a base, a socket-engaging contractile and expansible head, a latch pivoted upon said stud and an inwardly bent ear integral with and extending from the periphery of 20 said base for holding said latch in assembled relation to said head.

9. A stud for a separable fastener including a base, a socket-engaging contractile and expansible head, a latch pivoted upon 25 said stud and an inwardly bent ear integral with and extending from the periphery of said base for holding said latch in assembled relation to said head, and means for securing said stud to a flexible carrying fabric, said means including a front plate presenting an imitation button to be pressed thereby to shift said stud and operate said latch when said stud is secured to a socket.

30 10. A separable fastener comprising, in combination, a socket presenting a stud-receiving aperture, a locking member and sealing disc normally urged into aperture-closing position by a spring, said locking member, sealing disc and spring forming part of 35 the socket assembly, a cooperating stud having a contractile and expansible head, a relatively long neck on said stud and a latch pivoted upon said stud, said head adapted to be locked in said aperture by said locking member and urged outwardly therefrom by said spring acting upon said sealing disc thereby permitting inward movement of said stud relative to said socket against the pressure of said spring to tip said latch thereby 40 shifting said locking member into unlocked position, for separation of said stud and socket.

50 11. A separable fastener comprising, in combination, a flush type socket presenting a front face having a stud-receiving aperture therethrough, a stud having a head contractile and expansible for engagement in said aperture, locking means forming part of the fastener assembly for locking said

stud and socket together, lock-shifting 60 means forming part of the fastener assembly, said lock-shifting means having a portion for engagement with the front face of the socket and another portion for engagement with the locking member whereby 65 movement of the stud toward the socket operates said lock-shifting means thereby displacing said locking means to permit separation of the fastener and means also forming part of the fastener assembly for cooperation with said lock-shifting means to prevent separation of said stud and socket when a lateral strain is exerted upon said stud.

12. A separable fastener comprising, in combination, a flush type socket presenting a front face having a stud-receiving aperture therethrough and an abutment formed on said front face, a cooperating stud having a head contractile and expansible for engagement in said aperture, locking means forming part of the fastener assembly to provide for locking said stud and socket together and lock-shifting means also forming a part of the fastener assembly, said lock-shifting means having one end thereof adapted to bear against said locking means and having its other end adapted to bear against the front face of said socket adjacent to said abutment to prevent separation of said stud and socket by resolution of forces arising from lateral stresses while being operable to displace said locking means and permit separation of the fastener by movement of one of the fastener members toward the other.

13. A separable fastener comprising, in combination, a socket including a casing presenting a stud-receiving aperture, an annular shoulder concentric with said aperture 100 at the front face of said casing and an axially movable locking member housed within said casing, a cooperating resilient stud having a latch pivoted thereon and bearing at one end against the socket casing between the aperture and said annular shoulder and cooperating with said shoulder to prevent tipping of said stud relative to said socket when lateral strain is exerted at that side thereof adjacent the latch and having its other end located within the stud for engagement with the locking member to displace it from locking engagement with the stud during separation of the fastener.

In testimony whereof, I have signed my 115 name to this specification.

FRED S. CARR.
